C. M. B. BOOS

SILO DOOR FRAME

Filed Aug. 31. 1921

Inventor:
Casper M. B. Boos.

By: Wallace R. Lane, Atty

UNITED STATES PATENT OFFICE.

CASPER M. B. BOOS, OF CHICAGO, ILLINOIS.

SILO-DOOR FRAME.

Application filed August 31, 1921. Serial No. 497,167.

To all whom it may concern:

Be it known that I, CASPER M. B. Boos, a citizen of the United States, residing at Chicago, in the county of Cook and State 5 of Illinois, have invented certain new and useful Improvements in Silo-Door Frames, of which the following is a specification.

My invention relates more particularly to a frame having provisions for holding and 10 permitting adjustments of the ends of stay wires or rods used in the construction of tile silos and the like, and aims more especially to produce a structure of the character stated which shall be easy, simple and 15 economical to manufacture; to provide a frame which shall have convenient means for the vertical adjustment of stay wires; to produce a structure convenient to use; and such further objects, advantages and 20 capabilities as will later more fully appear.

My invention further resides in the combination, construction and arrangement of parts illustrated in the accompanying drawing, and while I have shown therein a preferred embodiment I desire the same to be 25 understood as illustrative only and not as limiting my invention.

In the accompanying drawing:

Fig. 1 is a plan view of one of the embodiments of my invention.

Fig. 2 is a broken perspective view of the construction shown in Fig. 1.

Fig. 3 is a broken plan view showing a different kind of slide for holding the ends 35 of the stay wires.

Fig. 4 is a view similar to Fig. 3 showing another form of the holding means.

Referring more in detail to the annexed drawing, letter F represents the frame and 40 D the door, provided with a door locking means L. The frame F comprises a plurality of upright members 1, 2, 3, 4, secured together in pairs by means of spaced brace members 5. Members 1 to 4 inclusive are 45 preferably pieces of steel angle irons, perforated for the reception of bolts 6 or the like, which may permit a limited amount of adjustment in order that the side members of the frame may be made precisely parallel 50 and adjusted to exactly the right distance apart. As shown, the locking members L are secured to the door sections D and have a part 7 which may be rotated in the base portion in order to permit the door section 55 to be locked in place.

It is obvious from an inspection of the drawing that the pairs of members 1, 2 and 3, 4 are spaced sufficiently far apart to permit the holding members 8, 8^a or 8^b to be received and slide freely therein. These 60 forms illustrated are simply some of the forms which may be used in this connection, but those shown in Figs. 3 and 4 are considered preferable to the one shown in Fig. 2. If the frame is to be used with narrow 65 tile, angle irons 1 and 2 will be brought closer together by the use of stay irons 5 of proper length and distance between the perforations for the bolts 6, whereas if wide tiles are to be used the angle irons must be 70 placed farther apart and it will then be preferable to use the double angle irons, as shown in Fig. 4, in preference to the T irons shown in Fig. 3. Secured to members 8, 8^a or 8^b are the ends of stay wires or rods 9 as 75 shown in the various figures.

Secured to the inner faces of the inner angle irons by suitable means, as bolts 10, are facing strips 11 of non-metallic material, 80 the purpose of which is to keep the contents of the silo from coming in contact with the angle irons 2 or 4. The manner of securing these strips to the angle irons is immaterial and I have merely suggested the use of bolts 85 for this purpose.

It will be observed that smaller angle irons 12 are perforated and secured to angle irons 2 and 4 by means of bolts 6 or otherwise. These angle irons 12 serve as abutments for the door sections D to rest against, 90 thereby furnishing effective means for preventing the door sections from being forced outwardly by pressure from within.

It is also to be noted that with the form of holding member 8 shown in Figs. 1 and 95 2 it is possible to secure a certain amount of adjustment of the length of the stay wires 9, by varying the position of the nuts on the hook-members.

It will be evident from the drawing and 100 the foregoing description that I have provided a frame which is simple and economical to manufacture and easy to use, and one in which it is easy to secure proper vertical adjustment of the stay rods 9.

Having now described my invention, I 105 claim:

1. In a structure of the character described, a frame comprising pairs of spaced angle-irons at the sides of the frame, spaced 110

members of pre-determined lengths connected to said angle-irons for holding the angle-irons a given distance apart to provide for adjustably connecting stay means in the 5 pairs of angle-irons, and stay means adjustably connected thereto.

2. In a structure of the character described, side members held at a given distance from each other, each side member 10 comprising a pair of angle-irons spaced to form a slot for the reception of a stay-wire holding member, and means to hold the angle-irons at a given distance apart.

3. In a structure of the character described, side members held at a fixed distance from each other, each side member comprising a pair of angle-irons, means to hold the angle-irons at a fixed distance apart to form a slot therebetween, and stay-wire holding means adjustably slidable in the slot between the angle-irons, and stay-wires connected to said holding means.

4. In a frame, pairs of oppositely placed spaced angle-irons, spaced brace members 25 connecting the members of the pairs of angle-irons at fixed distances apart, brace rods connecting the pairs of angle-irons at substantially fixed distances apart, and stay-wire attaching members extending through 30 the slots between the angle-irons and slidably vertically therein.

5. In a structure of the character described, side members held at a fixed distance from each other, each side member

comprising a pair of angle-irons spaced to 35 form a slot for the reception of a stay-wire holding member, means to hold the angle-irons at a fixed distance apart, and other angle-irons secured to opposite ones of the first named angle-irons to form door rests. 40

6. In a structure of the character described, a frame comprising pairs of spaced angle-irons, space members connected to the angle-irons for holding them in spaced relation to form a guide slot therebetween, in 45 combination with non-metallic facing strips secured to the inner faces of the inner angle-irons.

7. A frame comprising a pair of side members, means adjustably holding the 50 members of each pair in given spaced relation, stay means being adjustably connected to and between said members, and means holding the pairs of members in spaced relation.

8. A frame comprising corner members, means holding said members in spaced relation, means slidably adjustable in the space between said members and connected to said members in adjusted positions, 60 and stay members connected to the slidably adjustable means.

In witness whereof, I hereunto subscribe my name to this specification.

CASPER M. B. BOOS.

Witness:

MERRILL M. BLACKBURN.
